UNITED STATES PATENT OFFICE.

OSKAR JUNGHANS, OF SCHRAMBERG, GERMANY.

CLOCKWORK-TESTING MACHINE.

Application filed August 7, 1924. Serial No. 750,792.

To all whom it may concern:

Be it known that I, Dr. OSKAR JUNGHANS, director, a citizen of the German Republic, residing at No. 134 of Gaishaldenerstrasse, Schramberg, Germany, have invented certain new and useful Improvements in Clockwork-Testing Machines, of which the following is a specification.

My invention relates to an improved 10 clock-work testing machine and my invention also includes a new and useful machine for carrying the improved method into effect.

The method hitherto employed for the 15 like purpose consists in hanging up a weight by a suitable member of the clock-work to be examined to actuate the latter so that the clock-work in itself, however, bodily remains at rest. This way of testing and regulating clock-works of this kind is not satisfactory and is objectionable for the reason that the clock-work in reality, that is to say, when actuated by centrifugal force owing to the flight of the projectile to 25 which it is attached, is subjected to conditions of motion and friction due to the quick revolutions, which must be taken into account and which cannot be taken care of in the method hitherto practised.

30 The object of my invention is to remedy this defect. With this aim in view or, in other words, in order to produce reliable and efficient clock-works for use in time fuses and the like, I examine and regulate 35 the clock-work, according to this invention, in such a manner that the prevailing conditions are similar to those of a flying projectile fitted with a time fuse having a clock-work of the kind under examination 40 or regulation.

Accordingly my invention, viewed from its broadest aspect, resides in causing the clock-work to be regulated to revolve, while in a locked state, that is to say with its 45 movable parts locked so that they will not run, then to be unlocked as soon as a rotary running speed similar to that in a flying projectile is attained, and thereupon to be locked again automatically, after a predetermined time the arrangement being such 50 that the single releasing or unlocking operations are successively accomplished by means of electrical power and at predetermined intervals or periods of time, whereby 55 a very simple and efficient construction of the machine designed for carrying out the

new method or invention will be obtained.

The accompanying drawings, forming a part of this specification, show for purposes of exemplification, a preferred form and manner in which my invention or method may be embodied and practised, but do not limit the claimed invention to such illustrative instance.

Figure 1 is an elevation of the machine, 65 partially in section, Figure 2 is a plan thereof with the auxiliary devices required for carrying out the new method, and a diagram of connections shown, Figure 2^a is a continuation of the wiring diagram of Figure 2, Figure 3 is an elevation of a part of the machine, Figure 4 is an end view thereof partly in section, and Figure 5 is a section taken on line 5—5 of Figure 1. Parts which are repeated in the several figures bear the same reference characters in each case.

Referring to Figures 1 and 2 the clock-work 1 to be regulated is clamped in and supported by a chuck 2 carried by the spindle 3¹ of a head stock 3. The spindle 3¹ is rotated, from any suitable source of power in the usual manner customary in lathes, preferably with the aid of an appropriate transmission and by means of a gear drive such as a centrifugal gear or the like adapted to produce a peripheral speed as required for the regulating purpose. In the tail stock 4 the back centre 5 is 80 securely mounted therein but is adapted to be adjusted axially by means of a rack and a pinion engaging therewith and operable by means of a hand wheel 6 as shown, the arrangement being such that the said back centre 5 can be fixed or locked in any adjusted position in the manner and by means 85 usual in the art so that the latter need not be illustrated or explained in detail.

The back centre 5 is hollow throughout its length and a second or internal back centre 7 is embedded to snugly fit therein. This centering member 7 is likewise hollow but not to the full extent of its length, and in the bore a coiled spring 7¹ is lodged acting to constantly force the member 7 in the direction towards the stationary head stock 3, whilst said member is likewise prevented from rotary movements within its carrier by any suitable means.

The rear or open end of the back centre 7 is slotted and a transverse bar 8 is inserted into the slot and securely attached to the

2
back centre 5 by means of screws or in any other appropriate way. The bar 8 serves as an abutment for the spring 7¹. The front end, that is the end on the left hand side in 5 Figure 1, of the inner back centre 7 projects beyond the end of the outer back centre 5 and is provided with a cup shaped member 9 rotatably mounted relative to the back centre 7 but coupled therewith so that 10 it cannot have any axial or lengthwise movability except with the member 7 as a unit.

The cup 9 is provided with two pins 9¹ firmly connected therewith and extending parallel to the axis thereof. The chuck 2 15 has two holes which are adapted to receive the two pins 9¹ whereby the cup can be coupled with the chuck in order to revolve in unison with the latter and the driving spindle 3¹. The rear end, that is the end on the 20 right hand side in Figure 1, of the inner back centre 7 is firmly connected with and carries a cross head 10 having two screws 11 axially displaceable and adjustable therein. A lever 12 fulcrumed in a transverse slot 25 5¹ at 45 of the back centre 5, see Figures 1 and 5, is adapted to engage in a transverse slot of the inner back centre 7 so as to lock and prevent the latter from moving lengthwise towards the stationary head stock under 30 the action of its spring 7¹. The lever 12 is provided with a spring 12¹, see Figure 5, which is adapted to impart to the lever the tendency of maintaining a depressed position in order to engage in the transverse slot 35 35 of the inner back centre 7. An electromagnet III is duly connected with the lever 12 so that, in case of energization, the lever will be caused to disengage from the slot and to thereby unlock the back centre 7, so that 40 the latter then will be free to move towards the chuck 2 under the action of its coiled spring 7¹. The electromagnet III and the operating parts belonging thereto are of conventional construction and arrangement 45 and therefore need not be described in detail.

Fulcrumed on the tail stock 4 are two bell crank levers 13 interconnected by tie bars to form a unit. This unitary double lever 13 is controlled by a powerful spring 14 attached 50 to the two outer and longer arms thereof and acting to pull the said arms downwardly while the two shorter and vertical arms of the double lever engage the hereinbefore mentioned screws 11, respectively, thus establishing 55 a tendency in the lever to move and displace the inner back centre 7 towards the right hand side in Figure 1 against the action of the spring 7¹.

A vertical rod 15 guided in suitable bearings 60 is provided below the double lever 13 and a pedal not shown is operatively connected with the rod 15. The construction and arrangements of the rod, the bearings, the connections and the pedal are of the usual 65 type known to persons skilled in the art and

to whom this specification is addressed so that a detail description thereof is deemed unnecessary. In operating the pedal the double lever 13 is turned about its fulcrum, against the action of the spring 14, so that the tie bar 13¹ interconnecting the extremities of the vertical arms of the double lever will be arrested by a spring controlled pawl or detent 16 pivoted to the tail stock and the double lever 13 will thus be locked 75 against the action of the spring 14 on releasing the pedal.

The pawl or detent 16 is keyed to one end of a shaft 16¹ and a two-armed lever 17 is firmly connected to the other end thereof. The shaft 16¹ is duly supported in bearings provided in brackets on the tail stock and a spring 17¹ is attached to the inner arm of the lever 17, that is the arm on the left hand side in Figure 3, the other end of said spring 17¹ being fixed to some stationary point of the machine. The spring 17¹ imparts to the lever 17 a tendency to hold the pawl 16 in engagement with the tie bar 13¹ of the double lever 13. The outer arm of the lever 17, 90 that is the arm on the right hand side of Figure 3, supports the armature 19 of an electromagnet IV which when energized will turn the lever 17 against the action of the spring 17¹ and thereby cause the pawl 16 to 95 disengage from the tie bar 13¹ of the double lever 13.

Two further electromagnets I and II are provided in the circuit of the electrical operating mechanism of the machine, the electromagnet I serving the purpose of initiating the beginning as well as the termination of the whole movement and the electromagnet II acting, in co-operation with the clock V, to effect the measurement of time of the 105 regulating operation and to control the other electromagnets.

The armature 20 of the electromagnet I is provided with two contact springs 21 and 22 insulated with relation to each other by 110 means of an insulated block 42, and a pawl 23 is pivoted to a stationary point to act as a means for engaging the armature and holding the same in its lowermost position, that is, liberated from the contact-pieces 43 and 44 as shown in Figure 2^a. At this position of the armature the two circuits controlled by the contacts 21 and 22 are open and adapted to be closed by disengaging the pawl 23 from the armature. The contact 22 acts to close the circuit of the electromagnet I while the contact 21 closes the main circuit including the clock V acting to produce by means of its second-pendulum 32, a short current impulse each second only. Such impulse flows through the coil of the electromagnet II so that the armature of this electromagnet will be attracted once each second whereby, through the agency of a pawl and ratchet mechanism 38, a shaft 24 properly 125 130

Journalled in stationary bearings is rotated, in the direction of the arrow in Figure 2, a short step each time the length of the step depending on the thickness of the single 5 tooth of the ratchet wheel or the pitch thereof.

The shaft 24 is included in the circuit and provided with three radial arms 25, 26 and 27 which are juxtaposed and adjustable in 10 their peripheral relation. Pivotally mounted on a post 28 or the like are three spring controlled contact pawls 25^a, 26^a and 27^a duly insulated with relation to each other and of which each is placed in a circuit of its own, 15 that is to say, in a different circuit, and adapted to come in contact with the corresponding arm 25, 26 or 27 of the stepwise revolving shaft 24. In Figure 2^a I have shown, for clearness sake, the three contact 20 pawls in superposed location but I wish to have it understood that in reality they are arranged in juxtaposition.

The operation of the machine is as follows:—

25 The clock-work to be regulated is clamped or otherwise secured in the clutch 2, a lever 18 being provided on the chuck for locking the balance of the clock-work. Then the back centre 5 together with the inner back 30 centre 7 located therewith by means of the lever 12, is to be fed towards the stationary head stock 3 by means of the hand wheel 6 until or so far that the cup 9 is in close proximity to the lever 18, the abutting 35 screws 11 are in close proximity to the lever 13 and the driving pins 9¹ of the cup 9 engage in their respective holes of the chuck, as will be seen in Figure 1. This done the back centre 5 is secured by clamping or in 40 any other suitable manner and the spindle 31 is then caused to rotate in the usual way known in lathes.

45 As soon as the spindle reaches the predetermined or required maximum value or number of revolutions the key 29, Figure 2^a, is depressed manually with the result that the depending arm 30 of the key pivoted to the pawl 23 closes a contact device 31 for the purpose of cutting off for the next movement the current to be supplied to the conduit, from the coil of the magnet I. On 50 continued depression of the key 29 the pawl 23 is disengaged from the armature of the electromagnet I and the armature thus released is lifted by its spring 27' whereby the circuit of the electromagnet II and of the clock V is closed by means of the contact 55 21, while the contact 22 at the same time acts to also close the circuit of the electromagnet I which, however, is diverted off by means of the contact device 31 and interrupted, the 60 next second through the energization of the magnet II and the feed motion of the arm 27.

65 Upon releasing the key 29 the armature of

the electromagnet II now accomplishes one stroke each second under the controlling action of the clock V—of which, for clearness sake, the pendulum only is shown in Figure 2^a—and causes, by means of the pawl 70 and ratchet device, the arm 25 to engage its contact pawl 25^a, whereby the electromagnet III will be energized, see Figures 2, 4 and 5, so that the armature of the latter acts to turn the lever 12 and to thereby disengage the same from the slot of the inner back centre 7. The thus released back centre 7 is pushed forwards by its spring 7¹ towards the stationary head stock 3 so that the rim of the cup 9 carried by the back centre 7, comes in contact with the lever 18 and disengages the same from the balance of the clock-work to be regulated with the result that the latter then will be free to run.

During the running of the work the armature of the electromagnet II continues to perform its successive second-movements until after a predetermined period or number of seconds the arm 26 of the pawl and ratchet mechanism engages its contact pawl 26^a 85 whereby the electromagnet IV will be energized. In consequence thereof the armature 19 of the electromagnet is attracted, the pawl 16 is disengaged by the armature from the tie bar 13¹ of the double lever 13 and the latter, thus released, tilts over under the action of the spring 14 to engage the screws 11 with the result that the inner back centre 7 together with the cup 9 are displaced in 90 the direction away from the stationary head stock until the lever 12 engages again in the slot of the back centre 7, so that the lever 18 of the chuck 2 will be released and catch at the balance to stop or lock the clock-work under test.

100 The apparatus now may be disconnected. The electromagnet II continues to be energized stepwise or intermittently in the meanwhile until the arm 27 of the pawl and ratchet mechanism engages its contact pawl 27^a in order to close the circuit of the magnet I. Immediately thereupon the latter attracts its armature whereby the whole circuit is interrupted, and the armature is then 105 locked in its attracted position by the pawl 23.

110 At the end of the regulating operation all the parts again take up the positions shown in the drawing, with the sole exception that the double lever 13 is tilted, over under the action of its spring 14 and its tie bar 13¹ is not engaged with the pawl 16. The back centre 5 after having been released, in the eventuality of still having been locked with 115 regard to the tail stock 4, is now returned, by means of the hand wheel 6, into its original or normal inoperative position with the cup 9 recessed from the clock-work to be regulated, so that the latter can be removed 120 from the chuck 2.

For the purpose of ascertaining the result of the test a disk 1¹ divided and marked in seconds may be employed. This disk is fixed to the outer end of the main shaft or spindle 5 of the clock-work to be tested so as to revolve therewith during the regulating or testing operation hereinbefore described. Upon removal of the clock-work from the chuck at the end of the operation it can be readily 10 seen from the disk 1¹, whether or not its rotary motion did correspond to the running time.

In order to accomplish a further testing operation the double lever 13 must be re- 15 turned by means of the pedal and the rod 15 into the position shown in Figure 1 with the tie bar 13¹ caught by the pawl 16. In connection with the described apparatus a device for ascertaining the interval between 20 the starting of the work and the impact of the firing pin 37 on a simulated primer 36 (Figure 2) may be employed. As shown in the drawing an insulated contact piece 32' attached to the cross head 10 is adapted to 25 close the circuit of an electromagnet VI by cooperating with a contact member 33 pro- 30 vided on the machine frame, as soon as the back centre 7 causes the clock-work to run owing to its advance in the direction towards 35 the spindle 3¹. The pivoted armature 40 of the said electromagnet VI is energized. But as soon as the firing pin of the fuse strikes the primer 36, the magnet VI will be cut out automatically so that the counter is stopped 40 and the interval between starting and stop- 45 ping can be read.

The means for automatically cutting out the electromagnet VI is of the following 40 construction and arrangement. The circuit of the electromagnet includes a contact piece 34 adapted to be opened by means of an auxiliary electromagnet VIII. The circuit of the latter leads, on the one hand, to the machine frame, that is the clock-work 1 and 45 the firing pin 37, and on the other hand to a brush 35 adapted to slide on an insulated slip-ring 38 mounted on the spindle 3¹. The slip-ring is electrically connected to a copper contact 36 (the simulated primer) by means 50 of an insulated conduit 39 passing through the spindle 3¹, the firing pin 37 when released to drop, meeting the said contact 36 and thus closing the circuit of the magnet VIII which in turn opens the contact 34 so 55 that the magnet VI will be deenergized.

From the foregoing it is believed that the advantages and novel features of my invention will be readily understood and, therefore, further detail description is deemed 60 unnecessary.

In reducing my invention to practice I find that the form described and shown is a most practical, efficient and preferred embodiment, but realizing that certain conditions will necessarily vary in concurrence 65

with the adaption of my machine, I desire to emphasize the fact that various minor changes in the details of construction and in the proportion of parts may be resorted to when required or desired without thereby 70 sacrificing any of the advantages of my invention as defined in the appended claims.

What I claim is:—

1. A method of testing the performance of 75 clock-works to be driven by centrifugal action, preferably for use in mechanical time fuses, consisting in causing a clock-work, while its running parts are in a locked condition, to revolve as a whole, unlocking the said running parts automatically when a rotary speed corresponding to that in a flying projectile is attained and locking the same again automatically after a predetermined running period.

2. A machine for testing the performance 80 of clock-works to be driven by centrifugal action, preferably for use in mechanical time fuses, comprising in combination and arranged in the manner of a lathe, a member for supporting and holding the clock-work 85 to be tested, means connected with the said member and adapted to lock and unlock the running mechanism of the said clock-work, a head stock with a spindle carrying the said member, a tail stock, two conaxial back centres supported in the latter, a rotatable coupling member at the one end of the one back centre, and a spring in the latter, substantially as and for the purpose set forth. 90

3. A machine for testing the performance 100 of clock-works to be driven by centrifugal action, preferably for use in mechanical time fuses, comprising in combination a chuck for supporting and holding the clock-work to be tested, a locking lever connected 105 with the said chuck and adapted to lock and unlock the running mechanism of the said clock-work, a head stock with a spindle carrying the said chuck, a tail stock, two con- 110 axial back centres supported in the latter, a rotatable coupling member at the one end of the one back centre, and a spring in the latter, substantially as and for the purpose set forth.

4. A machine for testing the performance 115 of clock-works to be driven by centrifugal action, preferably for use in mechanical time fuses, comprising in combination a chuck for supporting and holding the clock-work to be tested, a locking lever connected to the 120 said chuck and adapted to lock and unlock the running mechanism of the said clock-work, a head stock with a spindle carrying the said chuck, a tail stock, two hollow back centres conaxially arranged the one within the other one and supported in the said tail- 125 stock, a rotatable coupling cup at the one end of the inner back centre, and a coiled spring in the latter, substantially as and for the purpose set forth. 130

5. A method of testing the performance of clock-works to determine the effects of centrifugal action which consists in the steps of rapidly rotating the clock-work to be tested, starting the clock-work to operate while under rapid rotation, and then stopping the operation of the clock-work after a predetermined running time.
6. A method of testing the performance of clock-works to determine the effects of centrifugal action which consists in the steps of rapidly rotating the clock-work at a predetermined speed, starting the clock-work to operate while under rapid rotation, and then stopping the operation of the clock-work after a predetermined running time.
7. A method of testing the performance of clock-works to determine the effects of centrifugal action which consists in the steps of rapidly rotating the clock-work at a predetermined speed and while the clock-work is in a non-running condition, automatically starting the clock-work to operate while under the uniform predetermined rotation, stopping the operation of the clock-work after a predetermined running time, and then stopping the rotation of the clock-work.
8. A machine for testing the performance of clock-works to be driven by centrifugal action, preferably for use in mechanical time fuses, comprising in combination a member for supporting and holding the clock-work to be tested, means connected to the said member and adapted to lock and unlock the running mechanism of the said clock-work, a stationary head stock with a spindle carrying the said member, a tail stock, two coaxial back centres supported in the latter, a rotatable coupling member at the one end of the one back centre, a spring in the latter, and a system of releasing electromagnets constructed and arranged substantially as set forth for the purpose specified.
9. A machine for testing the performance of clock-works to be driven by centrifugal action, preferably for use in mechanical time fuses, comprising in combination a member for supporting and holding the clock-work under examination, a means connected to the said member and adapted to lock the running mechanism of the said clock-work, a stationary head stock with a spindle carrying the said member, a tail stock, two coaxial back centres supported in the latter, a rotatable coupling member at one end of one of the back centres, a spring in the latter, an electrical system including releasing electromagnets, and a chronometer, the arrangement being such that the electromagnets are energized according to predetermined intervals controlled by the said chronometer, substantially as and for the purpose set forth.
10. A machine for testing the performance of clock-works to be driven by centrifugal action, preferably for use in mechanical time fuses, comprising in combination a member for supporting and holding the clock-work under examination, a means connected to the said member and adapted to lock the running mechanism of the said clock-work, a stationary head stock with a spindle carrying the said member, a tail stock, two coaxial back centres supported in the latter, a rotatable coupling member at the end of one of the back centres, a spring in the latter, an electrical system including releasing electromagnets, a chronometer, and a pawl and ratchet device, the arrangement being such, that the said chronometer actuates, by means of one of the electromagnets, the said pawl and ratchet device in order to close the circuits of the several electromagnets in a predetermined succession, substantially as and for the purpose set forth.
11. A machine for testing the performance of clock-works to determine the effects of centrifugal action comprising a head stock, a chuck rotatably mounted in said head stock and adapted to receive the clock-work to be tested, a lever on the chuck for locking and unlocking the balance of the clock-work, a tail stock associated with said head stock, a cup in said tail stock adapted to be coupled with the chuck and movable axially, and means for moving said cup against the lever in order to release the balance of the clock-work.
12. A machine for testing the performance of clock-works to determine the effects of centrifugal action comprising a lathe which is adapted to rotate the clock-work to be tested at a predetermined speed, means associated with the lathe for locking and unlocking the balance of the clock-work to be tested while the clock-work is in rotation; and means for timing the operation of the lathe.
13. A machine for testing the performance of clock-works to determine the effects of centrifugal action comprising a lathe which is adapted to rotate the clock-work, means for locking the balance of the clock-work to be tested during rotation, and means for actuating the first-named means for unlocking the balance during rotation, said two means being associated with the lathe.
14. A machine for testing the performance of clock-works to determine the effects of centrifugal action comprising a lathe which is adapted to rotate the clock-work, a lever pivotally mounted on a chuck of said lathe and adapted to lock the balance of the clock-work, and means for actuating the lever while the clock-work is rotating.
15. A machine for testing the performance of clock-works to determine the effects of centrifugal action comprising a lathe which is adapted to rotate the clock-work, means

in the lathe for locking and unlocking the balance of the clock-work, an electrical circuit associated with said lathe comprising an electro-magnet, a pendulum of a clock, a pair of contacts, said electro-magnet being adapted to close the circuit through the pendulum and the contacts, and a second electro-magnet operated by the successive closing of the contacts with the pendulum and adapted to operate the means to unlock the balance of the clock-work.

16. A machine for testing the performance of clock-works to determine the effects of centrifugal action comprising a lathe which is adapted to rotate the clock-work and having locking and unlocking means associated therewith, and an electrical circuit associated with the lathe comprising an electro-magnet, a pendulum of a clock, a pair of contacts, said electro-magnet being adapted to close the circuit through the pendulum and the contacts, and a second electro-magnet operated by the successive closing of the contacts with the pendulum which is adapted to operate the locking and unlocking means of the lathe.

17. A machine for testing the performance of clock-works to determine the effects of centrifugal action comprising means for rotating the clock-work to be tested and having locking and unlocking means for the balance of the clock-work; and an electrical system comprising means for operating the unlocking means in order that the clock-work may operate, and means for locking the balance of the clock-work after a predetermined running time.

18. A machine for testing the performance of clock-works to determine the effects of centrifugal action comprising means for rotating the clock-work to be tested and having locking and unlocking means for the balance of the clock-work; and an electrical system comprising means for operating the unlocking means in order that the clock-work may operate, a second circuit, a pendulum of a clock for timing the duration of the test, said second circuit being controlled by the pendulum and is switched in by said means of the electrical system, and means for locking the balance of the clock-work after a predetermined running time.

19. A machine for testing the performance of clock-works to determine the effects of centrifugal action comprising means for rotating the clock-work to be tested and having locking and unlocking means for the balance of the clock-work; and an electrical system comprising an electro-magnet, a second circuit controlled by said electro-magnet, a pendulum of a clock for timing the duration of the test and which is adapted to control said second circuit, and a second electro-magnet for locking and unlocking the balance of the clock-work.

20. A machine for testing the performance of clock-works to determine the effects of centrifugal action comprising a lathe for rotating the clock-work to be tested and having locking and unlocking means for the balance of the clock-work; electro-magnets adapted to operate said means; and an electrical system comprising an electro-magnet, a second circuit controlled by said electro-magnet of said system, a pendulum of a clock for timing the duration of the test, and a second electro-magnet for energizing the magnets which control the locking and unlocking of the balance of the clock-work.

21. A machine for testing the performance of clock-works to determine the effects of centrifugal action comprising a lathe for rotating the clock-work to be tested and having locking and unlocking means for the balance of the clock-work; electro-magnets adapted to operate said means; and an electrical system comprising an electro-magnet, a pendulum of a clock for timing the duration of the test, a second circuit controlled by said pendulum, and a second electro-magnet actuated by the oscillation of the pendulum and adapted to close successive contacts which are in circuit with the magnets of the locking and unlocking means of the lathe.

22. A machine for testing the performance of clock-works to determine the effects of centrifugal action comprising a lathe for rotating the clock-work to be tested and having locking and unlocking means for the balance of the clock-work; electro-magnets adapted to operate said means; and an electrical system comprising an electro-magnet, a pendulum of a clock for timing the duration of the test, a second circuit controlled by said pendulum, a switch for operating the last-named electro-magnet, and a second electro-magnet actuated by the oscillation of the pendulum and adapted to close successive contacts which are in circuit with the magnets of the locking and unlocking means of the lathe.

23. A machine for testing the performance of clock-works to determine the effects of centrifugal action comprising a lathe for rotating the clock-work to be tested and having locking and unlocking means for the balance of the clock-work; electro-magnets adapted to operate said means; and an electrical system comprising an electro-magnet, a pendulum of a clock for timing the duration of the test, a second circuit controlled by said pendulum and said last-named electro-magnet, a pair of contacts adapted to operate with said pendulum for closing a circuit at each end of an oscillation, and a second electro-magnet actuated by the closing of the circuit of the pendulum and its contacts and adapted to close successive contacts which are in circuit with the magnets

- of the locking and unlocking means of the lathe.
24. A machine for testing the performance of clock-works to determine the effects of centrifugal action comprising a lathe for rotating the clock-work to be tested and having locking and unlocking means for the balance of the clock-work; electro-magnets adapted to operate said means; and an electrical system comprising an electro-magnet, a pendulum of a clock for timing the duration of the test, a second circuit controlled by said pendulum and said last-named electro-magnet, a pair of contacts adapted to operate with said pendulum for closing a circuit at each end of an oscillation, a switch for operating the last-named electro-magnet, and a second electro-magnet actuated by the closing of the circuit of the pendulum and its contacts and adapted to close successive contacts which are in circuit with the magnets of the locking and unlocking means of the lathe.
25. A machine for testing the performance of clock-works to determine the effects of centrifugal action comprising a device for rotating the clock-work to be tested at a predetermined speed, and means associated with said device for locking and unlocking the balance of the clock-work to be tested while the clock-work is rotating.

In testimony whereof I affix my signature.

OSKAR JUNGHANS.
